COMBINED SOLE AND ARCH CONSTRUCTION FOR SHOES

Joseph Ruig Rigandi, Westerleigh, N. Y.

Application June 10, 1936, Serial No. 84,393

8 Claims. (Cl. 36—71)

The present invention relates to new and useful improvements in shoes and more particularly it pertains to a new and novel construction of combined sole and arch supporter.

5 It is the primary object of the invention to provide a novel construction in shoes for the purpose of building into the shoe an arch supporter.

Other objects of the invention will appear as the nature thereof is better understood for which 10 purpose reference will be had to the following specification and claims and the accompanying drawings, wherein:

Figure 1 is a view in elevation partly in section of the front portion of a shoe which is constructed 15 in accordance with the present invention,

Figure 2 is a detail sectional view taken substantially on the line 2—2 of Figure 1,

Figure 3 is a detail transverse sectional view of 20 a shoe constructed in accordance with the present invention,

Figure 4 is a view in side elevation of an insole embodying the improved construction,

Figure 5 is a bottom plan view of an insole embodying the improved construction,

25 Figure 6 is a transverse sectional view taken substantially on the line 6—6 of Figure 4,

Figure 7 is a longitudinal sectional view on an enlarged scale taken substantially on the line 1—1 of Figure 5,

30 Figure 8 is a plan view illustrating a modified form of construction,

Figure 9 is a view in side elevation illustrating that form of the invention shown in Figure 8,

Figure 10 is a bottom plan view partly broken 35 away showing that form of the invention illustrated in Figures 8 and 9,

Figure 11 is a transverse sectional view taken substantially on the line 11—11 of Figure 9,

Figure 12 is a detail longitudinal sectional view 40 taken substantially on the line 12—12 of Figure 8,

Figure 13 is a plan view illustrating a still further modified form of the invention,

Figure 14 is a transverse sectional view taken 45 substantially on the line 14—14 of Figure 13,

Figure 15 is a detail longitudinal sectional view on an enlarged scale taken substantially on the line 15—15 of Figure 13,

Figure 16 is a bottom plan view partly broken 50 away illustrating the detail construction of the modified form shown in Figures 13 to 17, inclusive,

Figure 17 is a detail perspective view, and;

55 Figure 18 is a transverse sectional view through the heel portion of a shoe constructed in accord-

ance with that form of the invention illustrated in Figures 15 through 17.

Referring specifically to the drawings by reference character, and more particularly to Figures 1 through 7, inclusive, the reference numeral 20 designates the upper of the shoe, the same having a lining 21. 22 designates an insole which has a lining 23 to which is secured by stitching 24 a skeleton sole member 25. Secured to the skeleton sole member there is a welt 26 and to this welt 10 26 the outer sole 27 of the shoe is secured. Interposed between the outer sole and the insole 22 there is a suitable pad or filling material 28.

By reference to Figures 4 to 6, inclusive, it will be noted that the insole 22 is formed at a 15 point intermediate its ends with an arch portion 23' which may be formed in the shoe in any desired manner preferably by moulding the insole at this point. By reference to Figure 5 it will be noted that the skeleton sole member 25 comprises 20 a relatively narrow body portion which conforms in shape to the shape of the insole and is secured thereto by the stitching 24 in such a manner that the skeleton sole member defines the outer edge of the insole 22. The inner wall or 25 edge of the skeleton sole is undercut as designated by the reference character 30', in the drawings. The lining 23 which is of fabric or any suitable material is secured to the insole preferably by cementing. This lining covers the area defined 30 by the skeleton sole member 25 and also, as shown at 31 in Figure 6, forms a lining for the undercut inner edge walls of the skeleton sole member 25. This construction provides an area 32 within the confines of the skeleton sole member 25 and when 35 the outer sole 27 is placed in position, this construction would provide a space in the area 32 if it were not for the filler 28. This filler 28 may be of any suitable compressible cushion material and is adapted to fill the space between the insole 40 22 and the outer sole 27, as best illustrated in Figure 2. This material may be secured in position in any desired manner.

The welt 26 heretofore mentioned is secured to the skeleton sole member 25 by suitable stitching 45 33 and the outer sole 27 is secured to the welt by suitable stitching 34. The stitching 33 which secures the welt 26 to the skeleton sole also secures the several elements of the upper 20 to the skeleton sole at a point between the insole and 50 the outer sole.

It will be noted that the skeleton sole 25 conforms to the shape of the insole 22 on the arched portion 23 thereof, and this construction provides a built-in arch support when the shoe is com- 55

pleted, which will serve to support the arch of the foot of the wearer.

In the form of the invention illustrated in Figures 8 to 12, inclusive, the insole 50 is formed with an arch portion 51 intermediate of its ends as in the heretofore described form of the invention. In this form of the invention, however, I employ a compressible arch supporting pad 52 of suitable compressible material. This arch supporting pad 52 is so shaped as to conform generally to the arch portion of the insole and is adapted to be received therein, as illustrated in Figure 9. This arch supporting pad 52 is preferably permanently fixed to the under face of the insole by cementing, although it may be secured thereto in any other desired manner. In this form of the invention the skeleton sole member is designated 55 and it is secured to the insole member 50 in substantially the same manner as in the heretofore described form of the invention except that at the point where the arch supporting pad is secured to the insole the skeleton sole member does not contact or engage the insole but instead passes across the arch supporting pad in such a manner that the arch supporting pad is interposed between the insole and the skeleton sole member. The skeleton sole member where it contacts with the arch supporting pad is secured thereto preferably by cementing so that the insole, the arch supporting pad and the skeleton sole member constitute a unitary structure. It is to be understood that the construction just described is secured in position in the shoe in the same manner as the previously described form of the invention and that when the shoe is completed, a built-in arch supporter results.

In that form of the invention illustrated in Figures 14 to 18, the insole is designated 60. This insole carries on its under face a skeleton sole member 61, which skeleton sole member has a continuous heel and shank portion 62. At its opposite end the insole 60 carries a skeleton heel member 63. This skeleton heel member comprises a relatively narrow strip cemented or otherwise secured to and conforming in shape to the heel portion of the insole.

In this form of the invention the arch supporting pad which is designated 65 is carried by an elongated member 66 having an opening 67 therein. This elongated member may be of a rigid material such as metal, or it may be of a semi-rigid nature if desired, and it is secured to the continuous heel and shank portion of the skeleton sole by suitable fastenings which pass through openings 68 in the ends of the elongated member, the fastenings being designated 69 in Figure 16. As shown in Figure 14 the arch supporting pad 65 has a head portion 70 which is adapted to be received in the opening 67 of the elongated member 66, and this means serves to position and hold in position the arch supporting pad 65.

This last described structure is adapted to be incorporated in a shoe in the same manner as the two forms heretofore described.

In Figure 18 I have illustrated a heel construction which consists of a plurality of lifts 80 which are secured by fastenings 81. The heel which comprises these several lifts is secured to the shoe upper 20 by fastenings 83. These fastenings 83 are preferably in the form of nails or tacks and by examining said Figure 18 it will be noted that when the fastenings 83 are driven home, their pointed ends will engage the elongated member 66 and will be turned over or clinched thereby.

From the foregoing it will be apparent that the

present invention provides a new and improved construction of combining an insole and arch support for shoes and that the objects of the invention are accomplished by the embodiments thereof herein illustrated.

Having thus described the invention what is claimed as new, is:

1. A combined sole and arch support construction comprising in combination, an insole having an arched portion intermediate of its ends, a relatively narrow skeleton sole member defining the edge of said insole member, said skeleton sole member having its inner edge undercut, and a compressible arch supporting pad secured to said insole at the arched portion thereof, said compressible supporting pad being interposed between the insole and the skeleton sole.

2. A combined sole and arch support construction comprising in combination, an insole having an arched portion intermediate of its ends, a relatively narrow skeleton sole member defining the edge of said insole member, said skeleton sole member having its inner edge undercut, and a compressible arch supporting pad secured to said insole at the arched portion thereof, said compressible supporting pad being interposed between the insole and the skeleton sole, said pad also being cemented to the skeleton sole member.

3. A combined sole and arch support construction comprising in combination, an insole having an arched portion intermediate of its ends, a skeleton sole member carried by said insole and defining the marginal edge thereof, an arch supporting element, and means for attaching the arch supporting element to said skeleton sole member.

4. A combined sole and arch support construction comprising in combination, an insole having an arched portion intermediate of its ends, a skeleton sole member carried by said insole and defining the marginal edge thereof, an arch supporting element, and means for attaching the arch supporting element to said skeleton sole member, said last mentioned means comprising an elongated body member for carrying said arch supporting element.

5. A combined sole and arch support construction comprising in combination, an insole having an arched portion intermediate of its ends, a skeleton sole member having a continuous shank and heel portion, a compressible arch supporting pad, means for carrying said arch supporting pad, and means for attaching said pad carrying means to said skeleton sole member with the pad disposed within the arched portion of the insole.

6. A combined sole and arch support construction comprising in combination, an insole having an arched portion intermediate of its ends, a skeleton sole member having a continuous shank and heel portion, a compressible arch supporting pad, means for carrying said arch supporting pad, means for attaching said pad carrying means to said skeleton sole member with the pad disposed within the arched portion of the insole, said last mentioned means comprising an elongated metal plate, and means for attaching said plate to the continuous shank and heel portion of the skeleton sole.

7. A combined sole and arch support construction comprising in combination, an insole having an arched portion intermediate of its ends, a skeleton sole member having a continuous shank and heel portion, a compressible arch supporting pad, means for carrying said arch supporting pad, means for attaching said pad carrying means to

said skeleton sole member with the pad disposed within the arched portion of the insole, said last mentioned means comprising an elongated metal plate having an opening therein for the reception of a projection on said arch supporting pad to secure the pad to the plate, and means for securing said plate at its ends to said skeleton sole at the continuous shank and heel portion thereof.

8. A combined sole and arch support construction comprising in combination, an insole, a skeleton sole member secured to said insole, said skeleton sole member having a continuous shank and

5 heel portion, a skeleton heel member comprising a relatively narrow strip defining the rear and side edges of the heel portion of the insole, said skeleton heel member serving to space the insole from the continuous shank and heel portion of the skeleton sole member, an elongated plate secured at its ends to the continuous portion of said skeleton sole member and positioned in the space between the continuous portion of said skeleton sole member and the insole, and an arch supporting pad carried by said elongated plate.
